Primary Examiner — Darlington Ly*(74) Attorney, Agent, or Firm* — Muncy, Geissler, Olds & Lowe, P.C.(57) **CLAIM**

The ornamental design for an electrically assisted bicycle, as shown and described.

DESCRIPTION

FIG. 1 is a perspective view of an electrically assisted bicycle showing my new design;

FIG. 2 is a right side view thereof;

FIG. 3 is a left side view thereof;

FIG. 4 is a top plan view thereof;

FIG. 5 is a bottom plan view thereof;

FIG. 6 is a front elevational view thereof; and,

FIG. 7 is a rear elevational view thereof.

1 Claim, 7 Drawing Sheets(56)
